UNITED STATES PATENT OFFICE.

CHARLES M. HYATT, OF ALBANY, NEW YORK, ASSIGNOR TO THE EMBOSSED COMPANY,
OF ALBANY, NEW YORK, A CORPORATION OF NEW YORK.

MANUFACTURE OF TOPS FOR BOTTLE-STOPPERS.

1,322,792.

Specification of Letters Patent. Patented Nov. 25, 1919.

Application filed December 11, 1918. Serial No. 266,291.

To all whom it may concern:

Be it known that I, CHARLES M. HYATT, a citizen of the United States, residing at Albany, county of Albany, and State of New York, have invented certain new and useful Improvements in the Manufacture of Tops for Bottle-Stoppers, of which the following is a full, clear, and exact description.

This invention relates to the manufacture of suitably finished and ornamented disks of wood for use as bottle-stopper tops, that is, disks to be glued or cemented to bottle-stoppers to provide a slightly finish therefor and afford convenient grasp for the fingers in removing and replacing the stopper. Heretofore wooden cork-tops, as they are sometimes called, have been produced by methods which leave them rough and unsightly. In some cases they have been incased in sheet metal, such as tin-plate, plain or embossed, but such casings or coverings as a rule add but little to the appearance of the bottle, and often they are a source of annoyance by reason of sharp metallic edges and corners which are liable to injure the fingers.

It is accordingly the chief object of the present invention to provide a stopper-top which will materially improve the appearance of the bottle and will afford convenient, easy and comfortable grasp for the fingers in removing and replacing the stopper. A further object is to provide a top having a highly polished surface but nevertheless capable of being securely fastened to the stopper with less glue or cement than has heretofore been possible, thus effecting a considerable economy. Still another object is to provide a simple and efficient method for making my improved stopper-tops, which will turn out the articles in large quantities with unfailing accuracy and uniformity. To these and other ends the invention consists in the novel article of manufacture and method and apparatus for making the same hereinafter described.

In the accompanying drawings I have illustrated two types of my improved top, and certain parts of a convenient and suitable apparatus for practising the method. In the drawings,

Figure 1 is a plan view, somewhat diagrammatic in character, of certain operative parts of the preferred apparatus for making my improved stopper-tops.

Fig. 2 is a section on line 2—2 of Fig. 1. Fig. 2a is a section on line 2a—2a of Fig. 1. Fig. 3 is a section, similar to Fig. 2, illustrating a tubular die for milling or corrugating the edges of the cork-tops.

Fig. 4 is a horizontal section on line 4—4 of Fig. 3.

Fig. 5 is a perspective view of one of the blanks from which the cork-tops are made.

Fig. 6 is a perspective view of a finished cork-top of polygonal contour.

Fig. 7 is a central cross section of a finished top.

Fig. 8 is a bottom plan view of a finished top, showing the large recess intended to fit down over the top of the cork or stopper, and the small recesses to receive the glue by which the disk is secured to the cork.

Fig. 9 is a top plan view of a finished cork-top having a milled edge.

The blanks from which the cork-tops are made are circular disks of wood, as 10, Fig. 5, preferably maple, sawed from turned cylindrical rods of suitable diameter, and are slightly larger in diameter and thickness than the finished tops are to be. The wood should be sound, straight-grained and free from knots, with the grain running axially, that is, perpendicular to the flat top and bottom faces. The wood must be thoroughly seasoned and the blanks dried,—in fact they should be "bone dry". The blanks are then stained, dyed, or colored, with suitable stain or pigment, if, as is usually the case, a finish other than "natural wood" is desired. The blanks may also be waterproofed by impregnating the surface with a suitable wax, as for example paraffin.

The apparatus shown in Figs. 1 and 2 comprises a tubular edge-forming die or sleeve 11, having at one side a table 12 to receive the blanks (indicated in dotted lines) which are fed intermittently from a chute 13. At the outer end of the table is a reciprocating pusher 14, actuated by any suitable means, not shown, by which the forward blank on the table is shifted into the open gripper 15 comprising a pair of spring-pressed jaws straddling the edge-forming die 11. The inward movement of the pusher is of such extent as to leave the blank directly over and co-axial with the aforesaid die 11, in which position it is held by the gripper.

A longitudinal rib 12a may be provided.

on the table 12 to guide the blank in its movement toward the gripper jaws. As the pusher moves in, it advances the first blank (indicated in dotted lines at 10, Fig. 1). 5 Upon its retraction the next blank moves into position, against the rib. A blank being over the die 11, the upper die 16 descends and forces the blank down into the die 11 and compresses it powerfully upon 10 the lower die 17. The cross-sectional area of the tubular edge-forming die 11 is smaller than the blank and its contour is that desired for the finished top. Moreover, the inner surface of the die, which is made of 15 material of suitable hardness and durability, such as hardened steel, is highly polished. The die shown in Figs. 1 and 2 is octagonal in cross section, but it will be understood that the invention is not limited in that respect. Suffice it to say that as the plunger or upper die comes down the blank is forced 20 into the flaring mouth of the die 11 and into the parallel-sided portion immediately below the flare. The movement being truly 25 axial, the blank undergoes a powerful radial compression, which is exerted at all points simultaneously, forcing the blank to take perfectly the contour of the die. As it is forced down its edges are subjected to a 30 hard rubbing on the highly polished walls of the die and are themselves given a polish. Finally the blank comes down upon the lower die 17 and is subjected to powerful pressure between said lower die 17 and the 35 upper die 16. One of these dies, for example the lower, has a central raised or cameo portion, as 18, circular in plan, so as to produce in the blank a circular recess, as 19, Figs. 7 and 8 to receive the top of the cork or bottle- 40 stopper 20 when the two are glued together as in Fig. 7. The other die may be shaped to produce the desired pattern in the upper surface of the disk, for example words, letters, or other characters; or an ornamental 45 design, such as the star shown in Fig. 6.

Both dies now rise, the lower rising just far enough to carry the finished top above the table and into the gripper, by which it is held as the lower die descends to its initial 50 position. The pusher then advances another blank, which latter pushes the finished top forward from its position over the mouth of the tubular die. As the operation proceeds the finished tops fall over the forward edge 55 of the table into a suitable receptacle not shown.

As described above, the edge of the top and its upper and lower surfaces may be shaped in the same operation, and the tubular edge forming die may have any desired contour—circular, or polygonal, etc.; or it may be ribbed, as in Fig. 3, to give a milled or corrugated edge to the stopper-tops. Or the edge may be shaped by a separate operation, before or after the plane surfaces

are shaped. For this purpose the devices illustrated in Fig. 3 may be used. In this figure the blanks are carried into the gripper 15 by the pusher 14 into position over the tubular edge-shaping die 11. The plunger 21 then descends, forcing the top down through the die. Usually the plunger can be cylindrical in form, but it may be shaped to fit the contour of the die, as may be necessary or desirable under the circumstances. 70 With a ribbed or corrugated die, such as is shown in Fig. 3, for example, the edge of the stopper-top is correspondingly ribbed or corrugated, as indicated in Fig. 9, which makes a pleasing finish and affords secure 80 grasp for the fingers.

To give the utmost security of attachment of the top to the cork or stopper, the under surface of the former is pitted, or provided with a plurality of small pits or recesses, 85 as indicated at 22, Figs. 7 and 8. Almost invariably in removing the stopper the user first gives it a twist, to loosen it in the bottleneck, and hence the greatest stress to which the top is subjected tends to twist or rotate 90 it relatively to the cork or stopper,—in other words a shearing stress. After it is loosened, the stopper in most cases is easily lifted out. The glue or other adhesive used penetrates into the recesses 22 and numerous 95 lugs or dowels, so to speak, are formed thereby, which effectually resist the shearing stress. The recesses provided for the purpose can be very shallow so as to require very little glue to fill them, and they are so 100 effectual that outside of them scarcely more than a film of glue is needed. The total amount of glue used is therefore greatly reduced, resulting in an important economy, especially where the tops are used in large 105 quantities, as has been amply demonstrated in practice. The recesses are preferably formed by the die which shapes the rest of the undersurface of the stopper-tops, for example the lower die 17, Fig. 2. For this 110 purpose said die is provided with the proper number of projections or bosses, as 23. By preference these projections are cylindrical in shape, producing cylindrical recesses. When a waxed blank is used, the wax with 1 which the surface outside of the recesses is coated does not give a secure hold for the adhesive; but in producing the recesses the projections 23 press small areas of the waxed surface into the body of the blank so that the side walls of the recesses are bare wood to which the glue or other adhesive used can adhere.

As before stated, the firm rubbing contact on the surface of the tubular edge-shaping 125 die not only shapes the edge of the stopper-top but also gives the same a pronounced polish. On the upper and lower surfaces the “finish” (as well as the shaping) is produced by the pressure of the upper and

lower dies, which pressure is powerful enough to impart to the blank the same "finish" as the dies themselves have, so that, for example, polished parts of the dies im-
5 part a polish to the corresponding parts of the blank. Rotation of the dies while their pressure is being exerted gives a somewhat higher polish but is in general unnecessary; and, indeed, is impossible unless the con-
10 tours of the pattern produced by the dies are truly circular and concentric.

It is to be understood that the invention is not limited to the details herein specifically described, but can be practised in other ways without departure from its spirit as defined by the following claims.

What I claim is:

1. As a new article of manufacture, a stopper-top consisting of a disk of wood compressed axially and radially and possessing the finish and configuration imparted by such compression, as set forth.
2. As a new article of manufacture, a stopper-top consisting of a disk of wood compressed axially and radially and possessing the finish and configuration imparted by such compression, and having on its underside a plurality of recesses for receiving adhesive material when secured thereby to 30 the stopper, as set forth.
3. As a new article of manufacture, a bottle-stopper consisting of a stopper and a top secured thereto by a suitable adhesive, said top consisting of a disk of wood compressed axially and radially and possessing the finish and configuration imparted by such compression and having on the surface next to the stopper a plurality of recesses, the adhesive extending into said recesses 40 and forming dowels to resist twisting of the top relatively to the stopper, as set forth.
4. The method of making stopper-tops of

the kind described, comprising forming a disk-shaped blank of axially grained bone-dry wood, surface-waxing the blank, forcing 45 the blank through a tubular die of less diameter whereby the blank is compressed radially to a smaller size and a permanent finish is imparted to its edge, and subjecting the upper and lower surfaces of the blank 50 to powerful pressure between upper and lower dies whereby permanent configuration and finish corresponding to the dies is imparted to said surfaces, as set forth.

5. The method of making stopper-tops of 55 the kind described, comprising forming a disk-shaped blank of axially grained wood; waxing the surface of the blank, forcing the blank through a tubular die of less diameter whereby the blank is compressed radially 60 to a smaller size and a permanent finish is imparted to its edge; and powerfully compressing the blank axially between upper and lower dies one of which is provided with a plurality of projections, whereby a 65 permanent finish and configuration is imparted to the blank, including a plurality of recesses on a surface thereof to receive adhesive when the top is secured to the stopper. 70

6. As a new article of manufacture, a stopper top consisting of a bone-dry surface-waxed disk of wood compressed axially and radially and possessing the configuration and finish imparted by the compression with 75 the wax pressed into the wood, and having in one face a plurality of recesses punched thereinto permitting adhesive to reach the unwaxed wood at the sides of the recesses when the top is glued to the stopper. 80

In testimony whereof I hereunto affix my signature.

CHARLES M. HYATT.
